UNITED STATES PATENT OFFICE.

ELLIOTT S. NORTON, OF CHICAGO, ILLINOIS, ASSIGNOR TO ACME STEEL GOODS COMPANY, OF CHICAGO, ILLINOIS, A CORPORATION OF ILLINOIS.

CORRUGATED-METAL FASTENER.

1,182,201.

Specification of Letters Patent.

Patented May 9, 1916.

Application filed December 4, 1906. Serial No. 346,293.

To all whom it may concern:

Be it known that I, ELLIOTT S. NORTON, a citizen of the United States, residing at Chicago, in the county of Cook and State 5 of Illinois, have invented certain new and useful Improvements in Corrugated-Metal Fasteners, of which the following is a specification.

The object of the present invention is to 10 produce a corrugated metal fastener of the "divergent" type having certain practical advantages hereinafter pointed out.

In the accompanying drawings Figure 1 represents the improved fastener in side elevation; Fig. 2 represents the same in end view; Fig. 3 represents the fastener in bottom plan view; Fig. 4 represents a portion of the fastener in side elevation on an enlarged scale; Fig 5 represents two pieces of 20 wood in section with a driven fastener in side elevation; and Fig. 6 represents two pieces of wood with the driven fastener in top plan.

Referring first to Fig. 1 the reference letter *a* designates a series of corrugations extending angularly across the metal strip, the reference letter *b* designates similar corrugations extending on the opposite angle and the reference letter *c* designates an intervening corrugation which is tapered from end to end. The fastener is beveled on opposite sides as indicated at *d* along that edge where the wide end of the corrugation *c* occurs. By so beveling the strip on opposite sides as shown in Fig. 2 a saw-tooth formation is effected. This results from the corrugations being cut away angularly to the same extent on both sides. Thus a series of sharp points *e* are produced and 40 between them substantially V-shaped cutting edges *f*. This is illustrated on an exaggerated scale in Fig. 4.

In Fig. 5 which illustrates the action of a fastener of the present invention 45 wherein the divergent feature is combined with the saw-tooth edge, the two pieces of soft wood *j* and *k* are represented closely drawn together as is found to be the case in practice. As this character of fastener is driven into the wood it is found that more or less lateral compression of the wood fibers takes place in the V-shaped portions which counteracts any tendency to give way before the cutting edges, the lat-

ter going cleanly through the fibers. It 55 therefore follows that the wood continues to hug the corrugations and hence the divergence of the latter is rendered extremely effective so that two pieces of wood will be tightly drawn together as illustrated in 60 this figure and in Fig. 6.

It is furthermore to be observed that the entering points *e* are all in the same straight-line, and that the side edges of the fastener run at right angles to this line. The driving edge of the fastener lies in a plane parallel with a similar transverse plane embracing said entering points. The straight-line character of the entering formation of the fastener, and also the right angle character 70 of the side edges, possess well recognized practical advantages over those prior forms of divergent corrugated fasteners having lengthwise convexity at the entering edge and corresponding angularity of side edges. 75 In setting the fastener upon the surface of the wood it is highly desirable that the full series of entering points or short edge sections shall engage that surface so as to insure a square setting of the fastener and 80 simultaneous penetration of all of these points in the interest of straight driving of the fastener into the wood. It is also desirable, particularly where the appearance counts in the article on which the fastener 85 is used, that no gaps be left in the wood. The right angle character of the side edges of my fastener insures against anything of this sort in straight driving of the fastener which is itself assured by the character of 90 the entering formation as above pointed out. Likewise the straight line character of the driving end of the fastener, besides affording the best character of head to strike in driving, will come exactly flush with the surface of the wood. All these advantages are 95 of special importance in a fastener having the divergent feature whose function is also to enhance the finish of the job by making a tight joint.

What is claimed is:

1. A corrugated metal fastener having an intermediate tapering corrugation and corrugations on opposite sides thereof parallel with the sides of the same respectively, said 105 fastener being beveled on opposite sides along the edge which embraces the wide end of the intermediate corrugation forming a

series of entering points with intervening draw-cutting edges, said points being all in straight-line with each other.

2. A corrugated metal fastener having an intermediate tapering corrugation and corrugations on opposite sides thereof parallel with the sides of the same respectively, said fastener being beveled on opposite sides along the edge which embraces the wide end 10 of the intermediate corrugation forming a series of entering points with intervening draw-cutting edges, said points being all in straight-line with each other, and the side edges of the fastener being at right angles 15 to said line.

3. A corrugated metal fastener having an intermediate tapering corrugation and corrugations on opposite sides thereof parallel with the sides of the same respectively, said 20 fastener having a sharpened entering formation embracing the wide end of the intermediate corrugation and lying throughout out in a plane transverse to the fastener.

4. A corrugated metal fastener having an intermediate tapering corrugation and corrugations on opposite sides thereof parallel with the sides of the same respectively, said fastener having a sharpened entering formation embracing the wide end of the intermediate corrugation and lying through- 25

out in a plane transverse to the fastener, and the side edges of the fastener being at right angles to said plane.

5. A corrugated metal fastener having an intermediate tapering corrugation and corrugations on opposite sides thereof parallel with the sides of the same respectively, said fastener having a sharpened entering formation embracing the wide end of the intermediate corrugation and lying throughout in a 40 plane transverse to the fastener, and said fastener having a driving edge lying in a similar plane. 35

6. A corrugated metal fastener having an intermediate tapering corrugation and corrugations on opposite sides thereof parallel with the sides of the same respectively, said fastener having a sharpened entering formation embracing the wide end of the intermediate corrugation and lying throughout in a plane transverse to the fastener, and said fastener having a driving edge lying in a similar plane, and the side edges of the fastener being at right angles to said planes. 45 50

ELLIOTT S. NORTON.
